PORTABLE HYDRAULIC TEST STAND

Kenneth C. Brock, 2536 N. Hollywood Way,
Burbank, Calif.

Filed Nov. 28, 1960, Ser. No. 63,001

Term of patent 14 years

(Cl. D14—3)

FIGURE 1 is a front elevation view of a portable hydraulic test stand, showing my new design;

FIGURE 2 is a rear elevation view thereof;

FIGURE 3 is an end elevation view thereof, as seen looking from the right of FIGURE 1, with a cover plate in an upright position;

FIGURE 4 is an end elevation view thereof, as seen looking from the right of FIGURE 2, with the control panel cover folded upward;

FIGURE 5 is an enlarged, fragmentary, front perspective view thereof; and

FIGURE 6 is a fragmentary side elevation view as seen along line 6—6 in FIGURE 5.

The dominant features of my design reside in the portions shown in full lines.

I claim:

The ornamental design for a portable hydraulic test stand, substantially as shown and described.
